UNITED STATES PATENT OFFICE.

CHARLES H. HAESELER, OF PHILADELPHIA, PENNSYLVANIA.

SELF-CLOSING VALVE.

1,171,116.

Specification of Letters Patent. Patented Feb. 8, 1916.

Application filed July 10, 1915. Serial No. 39,060.

To all whom it may concern:

Be it known that I, CHARLES H. HAESELER, a citizen of the United States, residing in the city and county of Philadelphia, State of Pennsylvania, have invented a new and useful Self-Closing Valve, of which the following is a specification.

My invention consists of a valve, faucet or cock for fluids in which the handle of the 10 plug will quickly close and open the same.

It further consists of such a valve in which the handle has movement in the plane of the hose and casing to prevent its projecting laterally and being tilted when striking an object when dragged on the ground.

It further consists of such a valve in which a screen at the receiving end of the duct of the casing is protected from injury.

It further consists of such a valve in 20 which the handle is locked when the valve-plug is open.

It further consists of other novel features of construction, all as will be hereinafter fully set forth.

25 The annexed drawings and the following description set forth in detail one mechanical form embodying the invention, such detail construction being but one of various mechanical forms in which the principle 80 of the invention may be used.

In said annexed drawings—Figure 1 represents an axial section of the valve or cock embodying my invention. Fig. 2 represents a transverse section on the line $x-x$, Fig. 1. 85 Fig. 3 represents an axial section of the strainer and its protective shell. Fig. 4 represents an end-view of such shell.

Similar numerals of reference indicate corresponding parts in the figures.

10 Referring to the drawings, the reference numeral 1 indicates a valve casing having a longitudinal bore, 2, and an exteriorly threaded neck, 3, at one end of the casing and a cylindrical recess, 4, at the other end 45 of the bore having a beveled shoulder, 5, and an interior screw-thread, 6, in the outer portion of the recess. A transverse cylindrical chamber or seat, 7, extends through the casing and intersects the longitudinal 50 bore, having one end partly closed and formed with a central opening, 8, in such closure. A tubular lining, 9, is fitted in said chamber and has diametrically opposite ports, 10, which register with the ends 55 of the longitudinal bore. A plug, 11, fits to slide within the chamber and has a re-

cess, 12, in its end into which one end of a coiled spring, 40, fits while the other end of the spring abuts against the inner face of the annular closure, 13, of the chamber. 60 A transverse bore, 14, is formed through the plug and is of the same diameter as the longitudinal bore and registers with the ports in the lining when the valve is pushed inward in its chamber. The outer end of 65 the valve-plug has a transverse groove, 15, formed with flanges, 16, on the sides of the groove and having arcuate concave edges, 20. Ears, 17, project from the end of the casing and an eccentric disk, 18, is pivoted 70 to oscillate between such ears upon a bolt, 19, passing through the ears and eccentrically through the disk.

The disk 18 has a flat edge 22 located diametrically opposite the portion contacting with the valve plug, when the parts are in the position seen in Fig. 1, it being apparent that when said handle and operating disk are rotated in the direction of the arrow seen in Fig. 1, or from left to right, 80 said flat edge will engage the bottom of the groove in the top of the valve plug, the latter being pressed outwardly by the spring 40, whereby said disk and plug will be effectively locked and prevented from accidental movement unless the handle 21 is manually or otherwise operated.

A cylindrical shell, 23, fits in the cylindrical recess of the valve-casing and is longitudinally movable in said recess, and an 90 annular plug or bushing, 24, has a threaded neck, 25, which is screwed in the screw-threaded recess 6 to retain the shell. The shell has a cylindrical wall, 26, and a preferably integral head, 27, formed with an 95 annular series of openings, 28, and the interior of the wall has an annular shoulder, 30, at the inner end of said wall. A foraminated metallic cap, 31, of woven wire or perforated sheet-metal fits with its flange 100 in the wall of the shell and bears against the shoulder 30, and an annular wall, 32, of a cap, 41, is fitted into the flange of the foraminated cap and has an annular series of openings 33 in its head and secures the 105 foraminated cap in the wall of the shell. The annular plug or bushing 24 has its screw-threaded inner portion 25 screwed into the outer threaded bore, 6, to lock the shell in its recess and has an enlargement, 36, 110 adapted to be engaged by a tool for turning it, and the inner bore, 37, of such nut is

screw-threaded to have the end of the air-hose secured in it.

In practice, the air-hose is connected to the bushing 24, and the percussion tool or other device to be driven is connected to the threaded neck. When the handle is tilted parallel to the bore of the valve, and with the short radius portion of the eccentric bearing against the end of the valve-plug, the spring 21 moves the faucet-plug upward and the valve is closed. When the handle is turned to bring the flat portion of the edge of the eccentric disk to bear against the plug to press it inward against the spring, the longitudinal bore of the casing and the transverse bore in the plug are brought to register with each other and the air or other motive fluid passes from the hose to the tool. The flat portion of the 15 edge of the eccentric disk will bear against the bottom of the groove in the end of the plug and be held from moving, and the motive fluid will be guided to the tool.

By tilting the lever backward, the flat 25 portion of the edge of the eccentric disk is brought to bear in the transverse groove and slides the plug to bring the transverse bore in the same out of register with the ports in the seat and close the passage through 30 the valve. As the handle swings in the plane of the ducts through the casing and plug and in the longitudinal direction of the faucet and hose, the handle will not turn or close the valve-plug if it strikes an 35 obstruction at the side of the hose, and the valve plug will not be changed from its adjusted position.

By placing the screen in the valve-casing removably in the passage through the casing 40 and within the shell, the impurities in the air will be arrested, and as the screen is protected at both sides by the perforated heads of the shell from being touched by fingers or tools by the operator, the screen 45 cannot be injured. To cleanse the screen, the annular plug or bushing 24 must be unscrewed, the shell removed from the annular recess, and the cap removed to have access to the screen. The insertion from 50 either end of the passage of the valve-casing of a metal or wooden rod cannot admit such rod to touch and injure the screen, and the shell must be taken apart to admit of the screen being touched.

While the structure is especially intended 55 for use with jack-hammers and drills and similar implements, it is evident that the valve may be employed in hose or similar conduits for cleaning the fluid passing 60 through it from dirt, sand or other impurities.

Other modes of applying the principle of my invention may be employed for the mode herein explained. Change may therefore be 65 made as regards the mechanism thus dis-

closed, provided the principles of construction set forth respectively in the following claims are employed.

Having thus described my invention, what I claim as new and desire to secure by Letters Patent, is:—

1. A fitting for pneumatic devices comprising a casing having a longitudinal bore therethrough, a valve seat extending transversely of said bore, a valve plug in said seat provided with a passage extending transversely therethrough, tension devices bearing on the opposite inner end of said valve, ears projecting from said casing, and a disk eccentrically mounted in said ears and having its edge engaging the top of said plug, said disk having its edge farthest from its fulcrum flattened to enable said valve plug to be locked in open position. 75

2. In a valve, a casing having a longitudinal bore therethrough, a valve seat extending transversely of said bore, a valve plug in said seat provided with a groove in its outer end, tension devices bearing on the opposite inner end of said valve, ears projecting from said casing, and a disk eccentrically mounted in said ears and having its edge engaging the groove in said plug, said disk having its edge farthest from its fulcrum flattened to enable said valve plug to 90 be locked in open position. 95

3. In a valve, a casing having a longitudinal bore therethrough, a valve seat extending transversely of said bore, a valve plug in said seat provided with a groove in its outer end, tension devices bearing on the opposite inner end of said valve, ears projecting from said casing, a disk eccentrically mounted in said ears and having its edge engaging the groove in said plug, said disk having its edge farthest from its fulcrum flattened to enable said valve plug to be locked in open position, and a handle on 100 said disk for operating the latter, said handle in both its extreme positions extending 105 in alinement with the longitudinal axis of said casing. 110

4. In a valve, a casing having a longitudinal bore therethrough, the inlet end of said bore being formed with a screen chamber, a screening device in said chamber, a valve seat extending transversely of said bore, a valve plug in said seat provided with a groove in its outer end, tension devices for the opposite inner end of said valve, ears projecting from said casing, and a disk eccentrically mounted in said ears and having its edge farthest from its fulcrum flattened to enable said valve plug to be locked 120 in open position. 115

5. In a valve, a casing having a longitudinal bore therethrough, the inlet end of said bore being formed with a screen chamber, a screening device in said chamber, means engaging the walls of said chamber 130

1,171,116

for retaining said screening device in position, a valve seat extending transversely of said bore, a valve plug in said seat provided with a groove in its outer end, tension devices for the opposite inner end of said valve, ears projecting from said casing, a disk eccentrically mounted in said ears and having its edge engaging the groove in said plug, said disk having its edge farthest from its fulcrum flattened to enable said valve

5
10

plug to be locked in open position, and a handle on said disk for operating the latter, said handle and disk in both their extreme positions extending in alignment with the longitudinal axis of said casing.
